UNITED STATES PATENT OFFICE.

MARTIN C. SCHWAB, OF CHICAGO, ILLINOIS, ASSIGNOR TO GRAVITY CONVEYOR COMPANY,
A CORPORATION OF NEW YORK.

DEFLECTOR FOR GRAVITY-CONVEYERS.

No. 927,176.

Specification of Letters Patent.

Patented July 6, 1909.

Application filed October 24, 1907. Serial No. 398,964.

To all whom it may concern:

Be it known that I, MARTIN C. SCHWAB, a citizen of the United States, residing at Chicago, in the county of Cook and State of Illinois, have invented a new and useful Improvement in Deflectors for Gravity-Conveyers, of which the following is a specification.

My invention relates to spiral gravity conveyers, and one of its objects is the provision of means to prevent the edges of door openings or door jambs from being struck by boxes or other articles in their descent through the conveyer.

Other objects will appear hereinafter, the novel combinations of elements being set forth in the appended claims.

Figure 1 is a sectional elevation of a portion of a spiral or gravity conveyer to which my invention is applied; Fig. 2 is a section taken on the line 2—2 of Fig. 1; and Fig. 3 is a section taken on the line 3—3 of Fig. 1.

The conveyer comprises an outer shell or casing 1, an inner core 2, and an interposed spiral blade 3. A door 4 hinged at 5 to the shell 1 is conveniently located between the floors 6, 6' as a closure for the intake opening of the conveyer. These parts are of usual construction.

It will be observed that the door is inclined in the direction of the adjacent portion of the spiral blade 3, and that the lower edge C of the door opening is a short distance above the blade 3. A guard or shield A is placed within the conveyer at or near the lower edge of the door. This guard is made preferably of sheet metal and comprises a wall or shield 7 mounted on the blade 3 in this instance perpendicular thereto, and extending the length of the intake opening or a short distance beyond each end of said opening. This vertical wall is preferably spaced from the casing 1 except at its ends, and as here shown is slightly curved toward the center of the conveyer. The upper edge of the shield 7 may be flush with the lower edge C of the door opening, and a flange B formed on the shield 7 extends to the edge C and forms a closure for the space between the shell 1 and the shield 7 to prevent articles which may be placed in the conveyer from dropping into the space between the shield and the casing 1. The guard may be secured in position in any desired manner, as for example by soldering or riveting.

The guard acts as a deflector for articles delivered to the conveyer which in their descent are thrown against the shell 1, and thus serves as a means for protecting the edges of the door openings or door jambs 60 from being struck by such articles, particularly heavy angular boxes and the like. It may also serve to protect descending articles from being injured by striking against the edges of door openings. In this instance I 65 have shown the upper surface B of the deflector conforming to the inclination of the intake opening and slightly below the edge C, although it may be flush therewith or above the same.

It should also be noted that the deflector need not have the flange B if the wall 7 is of sufficient height, is rigidly secured in position and extends downwardly along the blade 3 from a point above the door opening. 75 Furthermore, the wall 7 may be shortened in length so that one of its ends connects with the shell 1 or is adjacent thereto just above the upper vertical edge of the intake opening; or instead of a hollow or boxlike deflector as shown, a solid guard may be used and the lower portion cut off if desired.

Obviously those skilled in the art may make various changes in the details and arrangement of parts without departing from 85 the spirit and scope of my invention as defined by the claims, and I desire therefore not to be limited to the precise construction herein disclosed.

What I claim is:

1. The combination of a spiral conveying surface and an outer wall having an opening therein, and means for deflecting descending articles away from the said opening.
2. The combination of a spiral conveying surface and an inclosing casing having an opening therein, and means for preventing descending articles from striking the edges of said opening.
3. In a gravity conveyer, the combination 100 with an inclined conveying surface, of a casing formed with a lateral opening, and a guard within the casing at or near the opening.
4. In a gravity conveyer, the combination 105 with a tubular casing formed with a lateral door opening, of a spiral conveying surface extending past said opening, and a deflector in the casing at or near the opening.
5. In a gravity conveyer, the combination 110

- with a tubular casing, a spiral blade, and a door, of a guard in position to deflect articles away from the door in their descent through the conveyer.
5. 6. In a conveyer, the combination with a casing provided with a lateral door opening, of a spiral blade, and a guard or shield within the casing at or near said door opening.
7. In a conveyer, the combination with a 10 casing provided with a lateral door opening, and a spiral blade, of a shield substantially perpendicular to the spiral blade, and in a position in front of the door opening.
8. In a conveyer, the combination with a 15 casing formed with a door opening therein, and a spiral blade, of a guard wall or shield resting on the spiral blade and having one of its ends adjacent to or in contact with the said casing.
20. 9. In a conveyer, the combination with a casing formed with a door opening therein, and a spiral blade, of a guard wall or shield on the spiral blade substantially perpendicular thereto, positioned opposite the door and 25 extending the length thereof.
10. In a conveyer, the combination with a tubular casing formed with a door opening therein, and a spiral blade, of a guard wall or shield on the spiral blade substantially perpendicular thereto, having its ends adjacent to the opposite ends of the door, and inclined in a direction opposite to the adjacent wall of the casing.
30. 11. In a conveyer, the combination with a 35 casing and a spiral blade therein, said casing being provided with a lateral door opening having its lower edge a short distance above the adjacent portion of the spiral blade, of a guard or shield on the spiral blade substantially perpendicular thereto and having its 40 upper edge substantially flush with the lower edge of the door opening.
12. In a conveyer, the combination with a 45 casing and a spiral blade therein, said casing being formed with a lateral door opening, of
- a guard wall within the casing opposite the door opening and spaced apart therefrom, and a closure for the space between the guard wall and the door opening.
13. In a conveyer, the combination with a 50 casing and a spiral blade, said casing being provided with a lateral door opening, of a guard wall within the casing opposite the door opening and spaced apart therefrom, and a flange on the guard wall extending 55 across the space between the guard wall and door opening.
14. In a conveyer, the combination with a tubular casing and a spiral blade therein, said casing being formed with a lateral door 60 opening having its lower edge a short distance above the adjacent portion of the spiral blade, of a guard wall within the casing resting on the spiral blade substantially perpendicular thereto, opposite the door, spaced 65 apart from the door, and having its upper edge flush with the lower edge of the door, and a flange on the guard wall covering the space between the guard wall and the lower edge of the door opening.
15. The combination with a conveying 70 surface, of a deflector consisting of a curved body portion, and a flange having its free edge curved in the opposite direction.
16. The combination with a conveying 75 surface and an outer cylindrical casing, of a sheet metal deflector consisting of a body portion curved in the arc of a circle, a flange on one of the edges of the body portion, said flange being substantially perpendicular to the body portion and having its free edge curved in the opposite direction to the body portion and located adjacent to said casing.
- In testimony whereof, I have signed my name to this specification in the presence of 80 two subscribing witnesses.
- MARTIN C. SCHWAB.
